Primary Examiner — John R Yeh(74) *Attorney, Agent, or Firm* — Mark E. Bandy; Rankin Hill & Clark, LLP(57) **CLAIM**

The ornamental design for a cable housing, as shown and described.

DESCRIPTION

FIG. 1 is a front, right perspective view of my new design for a cable housing;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings depict portions of the cable housing that form no part of the claimed design.

1 Claim, 7 Drawing Sheets(56)
